ABSTRACT

Disclosed herein is a new monorail with plural bearing surfaces, one of which serves to guide and to support suspension (top supported or "below rail") railway vehicles and another which serves to guide and to support upright (bottom supported or "above rail") railway vehicles, all of which vehicles are powered by electrolinear motors energized through secondaries forming part of the new monorail.

MONORAIL

BACKGROUND OF THE INVENTION

A rail is known for suspension railways in which the rail forming the bearing surface of the suspension railway vehicle and the rail supporting the rollers for the traction chain constitute a single rail. This combination of the individual rail elements results in better material exploitation due to the increased moment of inertia of the larger rail. A disadvantage of this type of rail, however, is the fact that, on such a rail, railway vehicles can only move in one direction, and they require a common chain transmission.

SUMMARY OF THE PRESENT INVENTION

An object of the invention is to develop a monorail in which the vehicle carrying capacity is doubled by permitting simultaneous use of the monorail in two directions, even in branching line areas, by railway vehicles driven separately with quick starting and high stopping power by electrolinear motors. This is achieved by adding to the sides of the top and bottom of the rail horizontal secondaries for the electrolinear motors of the upright and suspension railway vehicles. This has been effected by adding bearing surfaces to a suspension monorail for additional use of the rail by upright (above rail or bottom supported) railway vehicles. The increased load on the new rail caused by carrying both upright and suspension vehicles does not require a substantial material increase, although the capacity of a single rail assembly may be doubled due to the simultaneous use of this assembly by upright and suspension vehicles. The arrangement of secondaries on both sides of the rail permit the crossing of branching lines, whereby one linear motor always contacts a secondary. The driving of the vehicles with electrolinear motors allows quick starts and stops of the vehicles even if they are equipped with wheels prone to sliding on the rail, for example, steel wheels.

As will be understood, by making double use of a single rail profile, only one rail is necessary, even for traffic in both directions. Thus, for railways intended for transportation of people in cities, the environment will not be affected as much as it would be with two rails running side by side. Moreover, side-by-side rails cannot readily bend around narrow street corners due to the fact that the curve of the inner rail cannot be inferior to the restricted curve radii.

A rail assembly constructed according to the principles of the present invention may be employed in such a way that upright and suspension railway vehicles are run in the same direction, for example, during rush hours.

The bearing surfaces or flange tracks for suspension and upright vehicles are preferably superimposed, in accordance with the invention. Furthermore, the invention contemplates the employment of the secondaries as stabilizing rails or flanges (auxiliary to the bearing surfaces of upright and suspension railway vehicles) for the prevention of tilting and swinging of the vehicles in cross winds and in traversing curves.

The profile of the new rail includes a generally vertically elongated box-shaped web profile; lower bearing surfaces for the wheels of the suspension railway vehicles and lower stabilizing rails forming a lower flight extending transversely outwardly of the mainly vertical members of the box web profile, and corresponding

upper bearing surfaces and stabilizing rails for the upright vehicles forming an upper flight extending transversely outwardly of the vertical members of the box web profile. The bearing surfaces or flange tracks for the wheels of upright and suspension vehicles may be externally attached to the vertical members of the box web profile and may be either angular profiles or strong flat profiles. This simple expedient allows the construction of a monorail profile which meets the required functions of support and guidance.

Other details of the invention provide the top and bottom portions of the new rail with secondary parts for the electrolinear motors of supported upright and suspension railway vehicles. The stabilizing rails may serve as electrical contacts which are arranged preferably on both sides of the vertical rail axis in order to assure uninterrupted motor energization and motion in the area of branching lines. In these branching line areas, there may be separate guide rails for auxiliary wheels of upright and suspension railway vehicles, which auxiliary wheels are arranged in such a manner that they may be moved crosswise on their axis, so that one of the auxiliary wheels takes over the guidance in the desired direction.

According to another detail of the invention, the new rail is reinforced with brackets attached to its sides between the upper and lower bearing surfaces, which brackets do not hinder the passage of upright and suspension railway vehicles. These brackets may be fastened to stable structures or supports, such as posts, columns, towers, etc. In order to avoid warping, both sides of the rail may be provided with brackets for separate supports.

A typical embodiment of the invention is shown in the accompanying drawings.

DESCRIPTION OF DRAWINGS

FIG. 1 is a side elevational, schematic view of one section of a rail assembly with upright and suspension vehicles traveling thereon in opposite directions; and

FIG. 2 is an enlarged, cross-sectional view of a rail embodying the principles of the invention with indications of upright and suspension railway vehicle carriages mounted thereon.

Referring now to FIG. 1, in the elevated new monorail, a plurality of upright vehicles A move to the left and a plurality of suspension vehicles B travel to the right. The distance between the vehicles may vary since each vehicle advantageously is self-propelled. The new rail is attached to the support C by means of laterally extending brackets 12, as will be understood and as illustrated in FIG. 2.

The box-shaped new monorail is formed mainly by vertical web members 1, upper flights 2a, 2b, and upper inverted U-profile 3a, 3b; lower flight 4a, 4b, and lower U-profile 5a, 5b. The upper flight or flange track 2a, as well as the lower flight or flange track 4a extend outwardly from members 1, and their extensions form bearing surfaces 2c and 4c for the wheels 6 of the upright and suspension vehicles A and B. The angular downturned ends of upper and lower flights 2a, 2b; 4a, 4b form guide rails 2d and 4d for the wheels 6. By means of stabilizing rails or auxiliary flanges 7, 7a and stabilizing wheels 8, 8a, the vehicles are protected against tilting.

In areas of branching lines, guide rails 9 for auxiliary wheels 10 are arranged adjacent the bearing surfaces

2c and 4c. The auxiliary wheels are movable crosswise on their axis with wheels 6. The elements 11, indicated in phantom, are usually provided only in the branching areas.

At the side of the new monorail, at the elevation of the wheels 6, sliding contact surfaces 13 are provided ensuring current supply via current pickups 14 to the electrolinear motors 15 which are attached to the upright and suspension railway vehicles and which work in conjunction with the secondary parts attached to or formed by stabilizing rails or auxiliary flanges 7 and 7a. The current pickups gliding along the sliding lines 13 are connected with the vehicles through conductor branches 17.

We claim:

1. A monorail adapted to support for propulsion therealong both top supported and bottom supported, wheeled, electrolinear motor-driven railway vehicles, said monorail comprising

- a. a hollow, elongated web of generally rectilinear cross section;
- b. an upper flight including an upper bearing surface for supporting the wheels of bottom supported vehicles;
- c. said upper bearing surface being an upper horizontal flange means extending bilaterally outwardly of upper portions of said web;
- d. a lower flight including a lower bearing surface for supporting the wheels of top supported vehicles;
- e. said lower bearing surface being a lower horizontal flange means extending bilaterally outwardly of the lower portions of said web;
- f. an upper stabilizing flange means extending bilaterally outwardly of said web and being disposed above and parallel with said upper bearing surface;
- g. a lower stabilizing flange means disposed below and being parallel with said lower bearing surface;
- h. said stabilizing flange means being adapted to function as secondaries of electrolinear motor

drives for said railway vehicles;

i. bracket means extending outwardly from said web between said upper and lower flights for supporting said monorail in an elevated position without interfering with the travel of top and bottom supported vehicles therealong.

2. A monorail according to claim 1, further characterized in that

a. said upper and lower bearing surfaces have shallow, inverted U-shaped cross sections.

3. A monorail according to claim 1, further characterized in that

a. said hollow web has a height in cross section substantially greater than its width in cross section to provide said web with a generally I-shaped appearance.

4. A monorail according to claim 1, further characterized in that

a. said bearing surfaces are of greater width than said stabilizing flange means.

5. A monorail according to claim 1, further characterized in that

a. said bracket means extends from both sides of said web.

6. A monorail according to claim 1, further characterized in that

a. said hollow web comprises two vertical side walls, an upper horizontal wall, and a lower horizontal wall;

b. said side walls are intersected and reinforced by said upper and lower flange means, to provide said web with a cross-sectional profile including three superimposed rectangles.

7. A monorail according to claim 1, further characterized in that

a. said stabilizing flange means are connected directly to said upper and lower web walls.
